US0D1032565S

(12) **United States Design Patent** (10) **Patent No.:** **US D1,032,565 S**
(45) **Date of Patent:** **** Jun. 25, 2024**

(54) **DOCK FOR HEADPHONES**

- (71) Applicant: **Dolby Laboratories Licensing Corporation**, San Francisco, CA (US)
- (72) Inventors: **Lucas E. Saule**, San Francisco, CA (US); **Vincent Voron**, Menlo Park, CA (US); **Peter Michaelian**, San Francisco, CA (US); **Guangyu Jin**, San Francisco, CA (US); **Kevin J. Kilpatrick**, Mountain View, CA (US); **Branko Lukic**, Menlo Park, CA (US); **Steven Ryutaro Takayama**, Menlo Park, CA (US); **Grayson H. Byrd**, San Francisco, CA (US); **Adam Scott Koniak**, Redwood City, CA (US); **Ariel Laurent Fischer**, San Francisco, CA (US); **Robert Edward Borchers**, Pleasanton, CA (US)
- (73) Assignee: **Dolby Laboratories Licensing Corporation**, San Francisco, CA (US)
- (**) Term: **15 Years**
- (21) Appl. No.: **29/765,326**
- (22) Filed: **Jan. 7, 2021**

Related U.S. Application Data

- (63) Continuation of application No. 29/662,267, filed on Sep. 4, 2018, now Pat. No. Des. 909,341.
- (51) **LOC (14) Cl.** **14-03**

(57) **CLAIM**

The ornamental design for a dock for headphones, as shown and described.

DESCRIPTION

FIG. 1 is a perspective view of a dock for headphones showing our new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The dashed broken lines illustrate structure or features which form no part of the claimed design.

The dot-dash broken lines illustrate boundaries which form no part of the claimed design.

1 Claim, 5 Drawing Sheets
